UNITED STATES PATENT OFFICE

2,456,695

BRASSIÈRE AND SIMILAR GARMENTS

Edwin W. Gluckin, Brooklyn, N. Y.

Application February 21, 1945, Serial No. 578,977

3 Claims. (Cl. 2-42)

1

This invention relates to garments employing breast supporting pockets or cups, with means for supporting the same upon the body of a wearer. More particularly, the invention deals with garments of this kind, wherein lower side portions of the pockets are subdivided to form relatively movable end portions with straps or bands for supporting said relatively movable end portions in supporting the breasts of a wearer in raised youthful position in the pockets when the garment is in use. Still more particularly, the invention deals with garments of the kind defined, wherein at least one of the strap members of the pockets constitute part of what might be termed a suspending unit having a free coupling at the upper central portion of the pocket and including a strap extending to the lower outer edge portion of the pocket or where the side band joins the pocket in providing of the suspending units a suspender-like structure to aid in support of the pockets upon the body of the wearer. The novel features of the invention will be best understood from the following description when taken together with the accompanying drawing, in which certain embodiments of the invention are disclosed, and in which the separate parts are designated by suitable reference characters in each of the views, and in which:

Fig. 1 is a front perspective view of one form of brassière which I employ with parts of the construction broken away.

Fig. 2 is an inside view of the brassière as seen in Fig. 1, showing the front portion thereof.

Fig. 3 is a perspective detailed view of the shoulder strap coupling with the brassière and suspending unit; and

Fig. 4 is a view similar to Fig. 2, showing a modified form of construction.

The present invention constitutes a continuation-in-part of the structure disclosed in, my prior application Serial Number 556,604, filed September 30, 1944, having matured in Patent 2,374,093 issued April 17, 1945.

In Figs. 1 and 2 of the drawing is shown front and rear views of at least the front portion of the garment or brassière. In these figures, 10 and 10a represent two substantially similar pockets joined centrally of the garment, as indicated at 11. Attached to outer side portions of the pockets are side and back bands 12 and 13 detachably coupled, as seen at 14 in any desired manner, as is customary in garments of this type and kind. One of the bands, for example, the band 13 may include an elastic insert 15 to provide yieldable mounting of the garment upon

2

the body of the wearer. At the upper central portion of each pocket is secured a strap or loop 16 and 17 with which is adjustably coupled shoulder straps 18 and 19 through the medium of buckles 20 and 21, the straps 18 and 19 being attached to the bands 12 and 13 at the rear portions thereof, as indicated at 22 and 23.

Each pocket at the lower central portion thereof has a dart 24 and 25 to give bust conforming contour to the pockets, and lower portions of the pockets below the darts have free relatively movable ends, the ends 26 and 27 being continuous with inner portions of the pockets and overlying outer side portions thereof, whereas said relatively movable ends which may be called parts or sides 28 and 29 terminate substantially in alignment with the darts 24 and 25. The ends 26 and 27 join the outer side edge portions of the pockets 10 and 10a in elastic straps 30 and 31. Attached to the ends 28 and 29 are elastic or Lastex straps or bands 32 and 33 with which are coupled strap members 34 and 35, which extend to and are coupled with the upper central portions of the pockets 10 and 10a, where the straps 16 and 17 are coupled therewith, the strap 34 extending to the upper end of the pocket 10a, and the strap 35 extending to the upper end of the pocket 10.

In addition to the straps 34 and 35, supplemental straps 36 and 37 are employed, which straps are joined with the upper ends of the straps 35 and 34, respectively, and to the side bands 12 and 13, preferably through the medium of elastic inserts 38 and 39, as clearly seen in Fig. 2 of the drawing.

From a consideration of Fig. 3 of the drawing, it will be apparent that the strap 16 is in the form of a loop which extends between the upper part of the pocket 10 and the joined ends of the straps 35 and 36. The strap 17 is of similar construction. This loop of the straps 16 and 17 freely passes through the buckles 20 and 21, thus providing an adjustment for independent support of the upper end of the pockets 10 and 10a and the suspending units comprising the straps 35 and 36, and 34 and 37. In other words, these suspending units are movable independently of the upper portions of the pockets in supporting the lower outer side portions of the pockets upon the breasts of a wearer. Part of this support is taken up through the bands 12 and 13 in forming a suspender-like mount of the brassière upon the body of the wearer.

In Fig. 4 of the drawing I have shown a slight modification wherein pockets 40 and 40a are

substantially identical in construction with the pockets 10 and 10a. In Fig. 4, 41 and 42 is equivalent to the parts 26 and 27, 43 and 44 the pocket ends similar to the ends 28 and 29, 45 and 46 straps equivalent to the straps 34 and 35, 47 and 48 straps equivalent to the straps 36 and 37, and supporting loops 49 and 50 similar to the loops 16 and 17. All other details of the several parts briefly described above are omitted for simplicity in description.

In Fig. 4, the modification consists simply in the addition of strap members 51 and 52, between the ends 43 and 44, and the outer side edges of the pockets or the side bands extending therefrom, the straps 51 and 52 preferably including elastic inserts 53 and 54. The straps 51 and 52 serve to provide additional supports for the outer lower side portions of the pockets to aid in supporting the breasts in raised position within the pockets. In other words, with the construction shown in Fig. 4, the breasts are substantially completely surrounded by supporting straps, the straps 51 and 52 acting in a sense as reinforcements and also balancing the strains to which the ends 43 and 44 are subjected by the lift upon the straps 45 and 46.

It will appear that the straps 51 and 52 join the outer side edges of the pockets at points above the attachment of the straps 47 and 48 therewith, as well as above the bounds of attachment of the elastic ends 55 and 56 of the strap extensions 41 and 42, and similar to the elastics 30-31. With both forms of construction shown, a positive suspender-like lift is provided for the brassière from lower side portions of the pockets, one strap of each suspender unit crossing a corresponding strap to an opposed unit centrally of the garment and extending to an opposed pocket, whereas the other strap of each suspender extends to the outer side edge portion or side band of the same pocket.

The suspender-like units operate independently of the lift upon the upper central portion of the pocket proper and yet by reason of the buckle coupling with the units and pockets, a compensating action is provided which establishes a balance resulting in the proper uplifting support of the breasts and relatively tight arrangement of the material of the pocket around the breasts.

Having fully described my invention, what I claim as new and desire to secure by Letters Patent is:

1. A brassière of the class described comprising a pair of similar breast pockets, means joining adjacent edge portions of the pockets, means attached to outer side edges and upper portions of the pockets for adjustably supporting the same upon the body of the wearer, each pocket having centrally of the lower portion thereof free relatively movable parts, each pocket having diverging suspending straps extending from the free outer part of one pocket to the upper central

portion of an opposed pocket and to the outer side edge of said opposed pocket, means adjustably coupling the suspending straps to each pocket, one strap of each pocket crossing the corresponding strap of an opposed pocket centrally between said pockets, and means coupling inner free portions of the pockets with outer edges thereof.

2. A brassière of the class described comprising a pair of similar breast pockets, means joining adjacent edge portions of the pockets, means attached to outer side edges and upper portions of the pockets for adjustably supporting the same upon the body of the wearer, each pocket having centrally of the lower portion thereof free relatively movable parts, each pocket having diverging suspending straps extending from the free outer part of one pocket to the upper central portion of an opposed pocket and to the outer side edge of said opposed pocket, means adjustably coupling the suspending straps to each pocket, one strap of each pocket crossing the corresponding strap of an opposed pocket centrally between said pockets, means coupling inner free portions of the pockets with outer edges thereof, and said last named means and the suspending straps of each pocket having extensible properties.

3. A brassière of the class described comprising a pair of similar breast pockets, means joining adjacent edge portions of the pockets, means attached to outer side edges and upper portions of the pockets for adjustably supporting the same upon the body of the wearer, each pocket including a pair of free downwardly diverging strap members, means centrally of the upper portion of each diverging strap member for coupling the same with the upper central portion of the pocket, one strap member of each pair extending from the upper central portion of the pocket to the lower edge portion of an opposed pocket, said strap members crossing centrally of the front of the garment, the other strap member in each pair, extending from the upper central portion of the pocket to the lower side edge of the same pocket, and said strap members including extensible material.

EDWIN W. GLUCKIN.
